INDEXABLE HEAD SWITCH

Michael J. Dobes, Cleveland Heights, Ohio, assignor to
The National Acme Company, a corporation of Ohio
Filed June 4, 1965, Ser. No. 461,389
17 Claims. (Cl. 200—47)

The invention relates in general to industrial switches, such as limit switches, and more particularly to a switch with a housing having a head which may be indexed into a plurality of positions.

In many industrial switch applications the switch mechanism is actuated by movement of some machine part, for example, a moving slide. The switch mechanism is mounted in a housing so as to be oil and dirt tight, as well as to provide mechanical and electrical protection to the actual switch. This is necessary in most machinery applications because of the environment in which the industrial switch is used. Also, the switch is subject to be used in many different positions and by all types of actuating slides or other apparatuses. Accordingly, different housings with different mounting hole arrangements were often used in the past in order to provide the necessary flexibility of mounting on any available surface for different actuating conditions. This required stocking additional housings to house the actual switch and increased manufacturing and inventory costs. Alternatively, if an actuating head were separate from a housing, it often was bolted to this housing and to change the position thereof relative to the housing, all bolts had to be removed, the head turned and then the bolts replaced.

Accordingly, an object of the invention is to provide a switch mechanism wherein an actuating head may be quickly indexed into any one of a number of plural positions to suit a number of actuating conditions.

Another object of the invention is to provide a switch mechanism with a single housing and single mounting means thereof onto a supporting surface, yet with the actuating head indexable into a plurality of positions to permit the switch to be actuated from a number of different directions.

Another object of the invention is to provide a switch mechanism with an indexing head which is urged into any of a number of positions by spring means.

Another object of the invention is to provide a switch mechanism with a spring means which provides a dual function of attaching a head to a switch housing and also permits the head to be indexed into plural positions relative to the housing.

Another object of the invention is to provide a switch mechanism with an indexable head on a housing with a means to rotatively lock the head to the housing and a means to axially lock the head to the housing, with the two means permitting ready removal of the head and ready indexing of the head relative to the housing.

The invention may be incorporated in a switch mechanism comprising, in combination, a housing; switch means mounted in said housing; an actuator on said switch means disposed for movement generally along an axis; an indexable head; a first wall on one of said housing and said head; a second mating wall on the other of said housing and said head; means to rotatively lock said head to said housing with said first and second walls in engagement; aperture means in said extension coaxial therewith; an actuator link in said head disposed in said aperture means in said extension to actuate said switch actuator; said rotative lock means including a plurality of recess walls symmetrical relative to said axis and defining recess means on one of said housing and said head, boss means on the other of said housing and said head entering said recess means to rotatively interlock therewith, and spring means urging said boss means into engagement with said

2

recess means; whereby said head may be moved axially to stress said spring means and to cause said boss means to be removed from said recess means to permit indexing of said head into any one of plural positions.

5 Other objects and a fuller understanding of the invention may be had by referring to the following description and claims, taken in conjunction with the accompanying drawings, in which:

FIGURE 1 is a side view partially broken away of a switch mechanism incorporating the invention;

FIGURE 2 is a top view with the cover removed of the switch of FIGURE 1;

FIGURE 3 is an end view of the switch housing with the head removed;

15 FIGURE 4 is a side view of an alternative head for the switch mechanism of FIGURES 1 and 2;

FIGURE 5 is a plan view of a spring to hold the head; and

FIGURE 6 is a side view of the spring of FIGURE 5.

20 FIGURES 1 and 2 generally show a switch mechanism 11 incorporating the invention. This switch mechanism includes generally a housing 12 and a head 13. The head 13 may be considered an actuating head to actuate a switch 14 contained within the housing 12. The head 13 may be referred to as a cam head. The switch 14 may be one of many varieties and includes generally an actuator plunger 17 movable generally along an axis 18 of the plunger 17. This axis 18 may be longitudinal of the housing 12 and parallel to an axis 19 of this housing 12.

25 The housing 12 is generally hollow and rectangular and has mounting holes 21 for mounting to any available surface, such as one on a machine. A cover 22 and cover gasket 23 may be provided to completely close the housing 12. This cover 22 is removed in FIGURE 2. A threaded

30 anerture 24 may be provided at one end of the housing 12 to receive the ordinary threaded conduit for mechanical protection to electrical conductors connecting to terminals 25 of the switch 14. The housing 12 has an end wall 28 at one longitudinal end of the housing. This may be called a first wall. The head 13 has a mating wall 29 to mate with this first wall 28. The first wall 28 has an interior surface 30 and an exterior surface 31. The interior surface 30 is generally rectangular. Means are provided to axially lock the head 13 on the housing 12

35 with the first and second walls 28 and 29 in mating engagement. Means are also provided to rotatively lock the head 13 to the housing 12. The housing wall 28 has a circular aperture 33 which is coaxial with the axis 18. The head 13 at the wall 29 has a cylindrical extension 34

40 which closely fits within the circular aperture 33 and is coaxial therewith. These parts are also shown on the roller head 51 of FIGURE 4, which is an alternative head mountable on the housing 12. An annular groove 35 is provided near the end of this cylindrical extension 34 and is defined at least partially by a cylindrical wall 36 and an annular shoulder 37. This annular shoulder is an outwardly facing shoulder, facing outwardly of the housing 12. With the head 13 mounted on the housing 12, the groove 35 is disposed inboard of the interior surface 30 of the housing end wall 28.

45 A leaf spring 39 is part of the means to axially lock the head 13 on the housing 12. This leaf spring 39 is better shown in FIGURES 5 and 6. It is generally flat and has a forked end 40 and a bight 41 of the fork which is generally semicylindrical and of a radius slightly larger than the cylindrical wall 36 forming part of the groove 35. The leaf spring 40 is generally rectangular in outline to be received against the rectangular inner wall 30. Spring 40 has an aperture 42 which, in use, may be positioned

50 close to the cover 22. This permits the leaf spring 39 to be grasped, as by a tool, at this aperture 42, so that the spring may be removed from the housing 12. The forked

end 40 of the spring 39 is bent at a small angle, for example, 10 degrees; and as shown in FIGURE 1, this permits the forked end to engage the interior surface 30 of the wall 28 at the same time that the bight of the fork engages the annular shoulder 37. This slightly stresses the spring 39, yet permits ready insertion of the spring into the housing 12 with the cover 22 removed. Also, this slight stressing of the spring axially locks the head 13 onto the housing 12. This stressing of the spring 39 permits the head 13 to be resiliently urged into engagement with the housing 12. With the cover 22 removed, the leaf spring 39 is readily removed and this permits the head 13 to be readily removed in an axial direction from the housing 12.

The means to rotatively lock the head 13 on the housing 12 includes boss means engaging with recess means generally at the mating walls 28 and 29. This rotative locking means is shown as including a recess 45 disposed in the first wall 28. This recess 45 is defined by recess walls 46 which define a polygonal recess, in this case shown as a square recess. These walls 46 are four in number with the recess being square and they may also be called shoulder walls. This square recess 45 is coaxial with the axis 18 and surrounds the circular aperture 33.

FIGURE 4 shows an alternative roller head 51 which may be substituted for the cam head 13. In order to mount this roller head 51 on the housing 12, it also has the cylindrical extension 34 and annular groove 35. This FIGURE 4 better shows the boss 52 on these heads 13 and 51 which will enter and mate with the recess 45. This boss 52 is a polygonal boss and in this case is shown as a square boss to mate with the square recess 45. The boss 52 has boss walls 53, shown to be four in number, defining the periphery of this boss 52. This boss 52 is concentric with the cylindrical extension 34 so as to be disposed in the recess 45 at the same time that the cylindrical extension 34 is disposed in the circular aperture 33.

The head 13 has aperture means 55 disposed along the axis 18 to slidably receive a link 56. This link is actuated in the head by a cam 57 to be moved longitudinally to act on the switch actuator plunger 17 to actuate the switch 14. The cam 57 may be actuated in turn by a lever 58 carrying a roller 59. The roller 59 is adapted to be actuated by some machine element, such as a slide or other movable member, not shown.

The roller head 51 contains a longitudinal slidable actuator link 61 carrying a roller 62 at the end opposite a cylindrical extension 34. This roller 62 may be actuated by some machine element, such as a slide, so that the actuator link 61 may move longitudinally and actuate the switch plunger 17.

OPERATION

The switch 11 may be mounted to a machine in any suitable manner, such as by bolts through the mounting holes 21. It may be mounted on any suitable mounting surface and these will vary widely depending upon the machine with which the industrial switch 11 is used. The actuating mechanism to actually strike the roller 59 or 62 of the cam head 13 or roller head 51 may also vary widely with the machine. Accordingly, it has been found that the switch mechanism 11 has definite advantages of being able to index the head 13 or 51, or any other of several actuating heads, into a plurality of positions. In the case of the switch shown, four positions are possible because of the square recess 45. The head 13 or 51 may be grasped and pulled axially outwardly to stress the spring 39. This will permit the boss 52 to be removed from the recess 45 and then this head may be turned into any one of four positions 90 degrees apart. This will dispose the lever 58 on different sides of the housing 12 and so permit the switch to be actuated from four different directions. This is a definite advantage in flexibility or actuation of the switch, because the surface on which the switch is mounted may not be parallel to the direction in which the actuating

slide is moved. Also, the head 51 may just as easily be indexed and this permits the roller 62 to be actuated by a slide mechanism moving in a direction to easily actuate the roller 62, rather than moving in a direction parallel to the bearing axis of the roller 62, which would break off the roller rather than actuating it.

The leaf spring 39 acts both in the means to rotatively lock the head and the means to axially lock the head to the housing 12. The spring 39 is slightly stressed in the normal position of assembly. This urges the head 13 axially toward the housing 12 to maintain a dirt-tight and generally oil-tight enclosure for the switch 14. The spring 39 is stressed still further when the head is pulled outwardly to remove the boss 52 from the recess 45. This permits the head 13 to be indexed into a plurality of positions.

Thus, the spring 39 serves a dual function permitting the head 13 to be readily removed and also to be readily indexed. The boss walls 53 are disposed in close proximity to the recess walls 46 under the urging of the

spring 39. This rotatively locks the head 13 in any one of plural positions. It will therefore, be seen that just one of these boss walls 53, cooperating with the corresponding recess wall 46, may be considered to be that which rotatively locks the head 13 in any one of plural positions

dependent upon the number of recess walls 46. The recess walls 46 are symmetrical relative to the axis 18 because the recess 45 is coaxial with the circular aperture 33. This symmetry permits the boss walls to mate with the recess walls for any one of the plural positions.

The forked end on the leaf spring 39 is a form of aperture in this leaf spring 39 permitting this spring to act between the annular shoulder 37 and the housing 12 at the end wall 28.

The present disclosure includes that contained in the appended claims, as well as that of the foregoing description.

Although this invention has been described in its preferred form with a certain degree of particularity, it is understood that the present disclosure of the preferred form has been made only by way of example and that numerous changes in the details of construction and the combination and arrangement of parts may be resorted to without departing from the spirit and the scope of the invention as hereinafter claimed.

What is claimed is:

1. A switch mechanism comprising, in combination: a housing; switch means mounted in said housing; an actuator on said switch means disposed for movement generally along an axis; an indexable head; a first wall on one of said housing and said head; a second mating wall on the other of said housing and said head; means to rotatively lock said head to said housing with said first and second walls in engagement; an extension on one of said walls extending through a coaxial aperture on the other of said walls, aperture means in said extension coaxial therewith; an actuator link in said head disposed in said aperture means in said extension to actuate said switch actuator; said rotative lock means including a plurality of recess walls symmetrical relative to said axis and defining recess means on one of said housing and said head, boss means on the other of said housing and said head entering said recess means to rotatively interlock therewith, and spring means urging said boss means into engagement with said recess means; whereby said head may be moved axially to stress said spring means and to cause said boss means to be removed from said recess means to permit indexing of said head into any one of plural positions.
2. A switch mechanism comprising, in combination,

a housing,
 switch means mounted in said housing,
 an actuator on said switch means disposed for move-
 ment generally along an axis,
 an indexable head,
 a first wall on one of said housing and said head,
 a second mating wall on the other of said housing and
 said head,
 means to axially lock said head on said housing with
 said first and second walls in engagement,
 means to rotatively lock said head to said housing,
 said axial lock means including an extension on one of
 said walls extending through a coaxial aperture on
 the other of said walls and including an outwardly
 facing shoulder on said extension engaged by spring
 means,
 aperture means in said extension coaxial therewith,
 an actuator link in said head disposed in said aperture
 means in said extension to actuate said switch actua-
 tor,
 said rotative lock means including boss means on one
 of said walls urged by said spring means into at least
 one of a plurality of recess walls symmetrical relative
 to said axis and defining recess means on the other of
 said walls, whereby said head may be moved axially
 to stress said spring means and to cause said boss
 means to be removed from said recess means to per-
 mit indexing of said head into any one of plural posi-
 tions equal to the number of recess walls.

3. A switch mechanism comprising, in combination,
 a housing;
 switch means mounted in said housing;
 an actuator on said switch means disposed for move-
 ment generally along an axis;
 an indexable head;
 a first wall on one of said housing and said head;
 a second mating wall on the other of said housing and
 said head;
 means to axially lock said head on said housing with
 said first and second walls in engagement;
 means to rotatively lock said head to said housing;
 said axial lock means including a circular aperture
 through said first wall,
 an extension on said second wall extending through
 said first wall aperture,
 an outwardly facing shoulder near the end of said ex-
 tension,
 and spring means engaging said shoulder and said first
 wall;
 aperture means in said extension coaxial therewith;
 an actuator link in said head disposed in said aperture
 means in said extension to actuate said switch ac-
 tuator;
 said rotative lock means including a plurality of recess
 walls symmetrical relative to said axis and defining
 recess means on one of said housing and said head,
 and boss means on the other of said housing and said
 head entering said recess means to rotatively inter-
 lock therewith;
 and said spring means urging said boss means into en-
 gagement with said recess means;
 whereby said head may be moved axially to stress said
 spring means and to cause said boss means to be removed
 from said recess means to permit indexing of said head
 into any one of plural positions equal to the number of
 recess walls.

4. A switch mechanism comprising, in combination,
 a housing,
 switch means mounted in said housing,
 an actuator on said switch means disposed for move-
 ment generally along an axis,
 an indexable head,
 a first wall on one of said housing and said head,
 a second mating wall on the other of said housing and
 said head,

means to axially lock said head on said housing with
 said first and second walls in engagement,
 means to rotatively lock said head to said housing,
 said axial lock means including an extension on one of
 said walls extending through a coaxial aperture on
 the other of said walls and including an outwardly
 facing shoulder on said extension engaged by spring
 means,
 aperture means in said extension coaxial therewith,
 an actuator link in said head disposed in said aperture
 means in said extension to actuate said switch ac-
 tuator,
 said rotative lock means including a plurality of recess
 walls symmetrical relative to said axis and defining
 recess means on one of said housing and said head
 and boss means on the other of said housing and said
 head urged into said recess means by said spring
 means to rotatively interlock therewith,
 whereby said head may be moved axially to stress said
 spring means and to cause said boss means to be removed
 from said recess means to permit indexing of said head
 into any one of plural positions equal to the number of
 recess walls.

5. A switch mechanism comprising, in combination,
 a housing,
 switch means mounted in said housing,
 an actuator on said switch means disposed for move-
 ment generally along an axis,
 an indexable head,
 a first wall on one of said housing and said head,
 a second wall on the other of said housing and said
 head,
 said first wall having an interior and an exterior sur-
 face,
 a circular aperture through said first wall coaxial with
 said switch actuator axis,
 an extension on said second wall closely fitting con-
 centrically within said circular aperture,
 aperture means in said extension coaxial therewith,
 an actuator link in said head disposed in said aperture
 means in said extension to actuate said switch ac-
 tuator,
 a plurality of recess walls symmetrical relative to said
 axis and defining recess means on one of said hous-
 ing and said head,
 boss means on the other of said housing and said head
 entering said recess means to rotatively interlock
 therewith,
 an outwardly facing shoulder on said extension and
 disposed inboard of the interior surface of said first
 wall,
 spring means urging said boss means into engagement
 with said recess means,
 and means including said spring means acting between
 said interior surface of said first wall and said shoul-
 der to retain said head on said housing,
 whereby said head may be moved axially to stress said
 spring means and to cause said boss means to be removed
 from said recess means to permit indexing of said head
 into any one of plural positions equal to the number of
 recess walls.

6. A switch mechanism comprising, in combination,
 a housing,
 switch means mounted in said housing,
 an actuator on said switch means disposed for move-
 ment along an axis,
 an indexable head,
 a first wall on one of said housing and said head,
 a second wall on the other of said housing and said
 head,
 said first wall having an interior and an exterior sur-
 face,
 a circular aperture through said first wall coaxial with
 said switch actuator axis,
 an extension on said second wall closely fitting con-
 centrically within said circular aperture,

aperture means in said extension coaxial therewith, an actuator link in said head disposed in said aperture means in said extension to actuate said switch actuator, 5
 a plurality of recess walls symmetrical relative to said axis and defining recess means on one of said housing and said head, 5
 boss means on the other of said housing and said head entering said recess means to rotatively interlock therewith, 10
 an outwardly facing shoulder on said extension and disposed inboard of the interior surface of said first wall, 10
 and means including spring means engaging said shoulder to lock said head on said housing in an axial direction and resiliently urging said head in one axial direction relative to said housing, 15
 whereby said head may be moved in the opposite axial direction to stress said spring and to cause said boss means to be removed from said recess means to permit indexing of said head into any one of plural positions equal to the number of recess walls. 20
 7. A switch mechanism comprising, in combination, a housing, 25
 switch means mounted in said housing, 25
 an actuator on said switch means disposed for movement along an axis, 25
 an indexable head, 25
 a first wall on one of said housing and said head, 25
 a second wall on the other of said housing and said head, 30
 said first wall having an interior and an exterior surface, 30
 a circular aperture through said first wall coaxial with said switch actuator axis, 35
 an extension on said second wall closely fitting concentrically within said circular aperture, 35
 a plurality of recess walls symmetrical relative to said axis and defining recess means on the exterior surface of one of said walls, 40
 boss means on the other of said walls entering said recess means to rotatively interlock therewith, 40
 wall means including an outwardly facing shoulder on said extension and disposed inboard of the interior surface of said first wall, 45
 a leaf spring having an aperture received over said extension and stressed between said interior surface of said first wall and said shoulder to resiliently urge said extension inwardly of said wall aperture, whereby said head may be pulled axially outwardly to stress said spring and to cause said boss means to be removed from said recess means to permit indexing of said head into any one of plural positions equal to the number of recess walls, 50
 aperture means in said extension coaxial therewith, and an actuator link in said head disposed for longitudinal sliding movement through said aperture means in said extension to actuate said switch actuator. 55
 8. A switch mechanism comprising, in combination, a housing, 60
 switch means mounted in said housing, 60
 an actuator on said switch means disposed for movement along an axis, 60
 a removable and indexable head, 60
 a first wall on one of said housing and said head, 65
 a second wall on the other of said housing and said head, 65
 said first wall having an interior and an exterior surface, 65
 a circular aperture through said first wall coaxial with said switch actuator axis, 70
 an extension on said second wall closely fitting concentrically within said circular aperture, 70
 a plurality of recess walls symmetrical relative to said axis and defining recess means on the exterior surface of one of said walls, 75

boss means on the other of said walls entering said recess means to rotatively interlock therewith, 8
 wall means including an outwardly facing shoulder on said extension and disposed inboard of the interior surface of said first wall, 8
 a leaf spring having a forked end having a dimension to be received against said shoulder, 8
 said leaf spring having one part engaging said interior surface of said first wall and another part engaging said shoulder to resiliently urge said extension inwardly of said aperture, whereby said head may be pulled axially outwardly to stress said spring and to cause said boss means to be removed from said recess means to permit indexing of said head into any one of plural positions and whereby said spring may be removed in a direction perpendicular to said axis to permit removal of said head from said housing along said axis, 15
 aperture means in said extension coaxial therewith, and an actuator link in said head disposed for longitudinal sliding movement through said aperture means in said extension to actuate said switch actuator. 20
 9. A switch mechanism comprising, in combination, a housing, 25
 switch means mounted in said housing, 25
 an actuator on said switch means disposed for movement along an axis, 25
 an indexable head, 25
 a first wall on one of said housing and said head, 25
 a second wall on the other of said housing and said head, 30
 said first wall having an interior and an exterior surface, 30
 a circular aperture through said first wall coaxial with said switch actuator axis, 35
 an extension on said second wall closely fitting concentrically within said circular aperture, 35
 a shoulder wall defining a polygonal recess on the exterior surface of one of said walls concentric with said aperture and extension, 40
 boss wall means on the other of said walls entering said polygonal recess to rotatively interlock therewith, 40
 wall means including an outwardly facing annular shoulder on said extension and disposed inboard of the interior surface of said first wall, 45
 a generally flat but slightly curved leaf spring having an aperture received over said extension, 45
 means to cause said leaf spring to act between and be slightly stressed between said interior surface of said first wall and said annular shoulder to resiliently urge said extension inwardly of said wall aperture, whereby said head may be pulled axially outwardly to further stress said spring and to cause said boss wall means to be removed from said recess to permit indexing of said head into any one of plural positions equal to the number of sides of said polygonal recess, 50
 aperture means in said extension coaxial therewith, and an actuator link in said head disposed for longitudinal sliding movement through said aperture means in said extension to actuate said switch actuator. 55
 10. A switch mechanism comprising, in combination, a housing, 60
 switch means mounted in said housing, 60
 an actuator on said switch means disposed for movement along an axis, 60
 a removable and indexable head, 60
 a first wall on one of said housing and said head, 65
 a second wall on the other of said housing and said head, 65
 said first wall having an interior and an exterior surface, 65
 a circular aperture through said first wall coaxial with said switch actuator axis, 70
 said leaf spring having one part engaging said interior surface of said first wall and another part engaging said shoulder to resiliently urge said extension inwardly of said aperture, whereby said head may be pulled axially outwardly to stress said spring and to cause said boss means to be removed from said recess means to permit indexing of said head into any one of plural positions and whereby said spring may be removed in a direction perpendicular to said axis to permit removal of said head from said housing along said axis, 75

and extension on said second wall closely fitting concentrically within said circular aperture, a shoulder wall defining a polygonal recess on the exterior surface of one of said walls concentric with said aperture and extension, 5
boss wall means on the other of said walls entering said polygonal recess to mate closely therewith, wall means including an outwardly facing annular shoulder on said extension and disposed inboard of the interior surface of said first wall, a generally flat leaf spring having a forked end with the bight of the fork having a dimension to be received against said annular shoulder, said forked end being bent at a small angle so that the two ends of the fork engage said interior surface of said first wall and the bight of the fork engages said annular shoulder to resiliently urge said extension inwardly of said aperture, whereby said head may be pulled axially outwardly to stress said spring and to cause said boss wall means to be removed from 15
said recess to permit indexing of said head into any one of plural positions equal to the number of sides of said polygonal recess and whereby said spring may be removed in a direction perpendicular to said axis to permit removal of said head from said housing along said axis, 20
aperture means in said extension coaxial therewith, and an actuator link in said head disposed for longitudinal sliding movement through said aperture means in said extension to actuate said switch actuator. 25
11. A switch mechanism comprising, in combination, a housing, switch means mounted in said housing, an actuator on said switch means disposed for movement along an axis, 30
a removable and indexable head, a first wall on one of said housing and said head, a second wall on the other of said housing and said head, 35
said first wall having an interior and an exterior surface, a circular aperture through said first wall coaxial with said actuator axis, a cylindrical extension on said second wall closely fitting concentrically within said circular aperture, a shoulder wall defining a polygonal recess on the exterior surface of one of said walls concentric with said aperture and extension, 40
boss wall means defining a polygonal boss on the other of said walls concentric with said aperture and said cylindrical extension and entering said polygonal recess to mate closely therewith, 45
wall means including an outwardly facing annular shoulder on said cylindrical extension and disposed inboard of the interior surface of said first wall, a generally flat leaf spring having a forked end with the bight of the fork having a dimension to be received against said annular shoulder, 50
said forked end being bent at a small angle so that the two ends of the fork engage said interior surface of said first wall and the bight of the fork engages said annular shoulder to resiliently urge said cylindrical extension inwardly of said aperture, whereby said head may be pulled axially outwardly to stress said spring and to cause said boss to be removed from 55
said recess to permit indexing of said head into any one of plural positions equal to the number of sides of said polygonal recess, 60
aperture means in said cylindrical extension coaxial therewith, and an actuator link in said head disposed for longitudinal sliding movement through said aperture means in said cylindrical extension to actuate said switch actuator. 65

12. A switch mechanism comprising, in combination, a housing, switch means mounted in said housing, an actuator plunger on said switch means disposed along an axis, an end wall at one longitudinal end of said housing and having an interior and an exterior surface, a circular aperture through said end wall coaxial with said plunger axis, a removable and indexable head on said end wall of said housing, a cylindrical extension on said head closely fitting within said circular aperture, boss wall means defining a polygonal boss, a shoulder wall defining a polygonal recess to mate closely with said boss, said boss being on one of said housing and said head, said recess being on the other of said housing and said head, wall means defining an outwardly facing annular shoulder on said cylindrical extension and disposed inboard of the inner surface of said housing end wall to be within said housing, spring means acting between said end wall interior surface and said annular shoulder to resiliently urge said head inwardly of said housing, whereby said head may be pulled axially outwardly to stress said spring means and to cause said boss to be removed from said recess to permit indexing of said head into any one of plural positions equal to the number of sides of said polygonal recess, 20
aperture means in said cylindrical extension co-axial therewith, and an actuator link in said head disposed for longitudinal sliding movement through said aperture means in said cylindrical extension to actuate said actuator plunger. 30
13. A switch mechanism comprising, in combination, a housing, switch means mounted in said housing, an actuator plunger on said switch means disposed along an axis, a removable and indexable head, a first wall on one of said housing and said head, a second wall on the other of said housing and said head, 35
said first wall having an interior and an exterior surface, a circular aperture through said first wall coaxial with said plunger axis, a cylindrical extension on said second wall closely fitting within said circular aperture, a shoulder wall defining a polygonal recess on the exterior surface of said first wall concentric with said aperture, 40
boss wall means defining a polygonal boss on said second wall concentric with said cylindrical extension and entering said polygonal recess to mate closely therewith, 45
wall means including an annular shoulder defining an annular groove on said cylindrical extension and disposed inboard of the interior surface of said first wall, 50
a generally flat leaf spring having a forked end with the bight of the fork having a dimension slightly larger than the diameter of said annular groove to be received in said annular groove, 55
said forked end being bent at a small angle so that the two ends of the fork engage said interior surface of said first wall and the bight of the fork engages said annular shoulder of said annular groove to resiliently urge said cylindrical extension inwardly of said aperture, whereby said head may be pulled axially outwardly to stress said spring and to cause said boss to be removed from said recess to permit indexing of said head into any one of plural positions 60

equal to the number of sides of said polygonal recess, aperture means in said cylindrical extension coaxial therewith,
and an actuator link in said head disposed for longitudinal sliding movement through said aperture means in said cylindrical extension to actuate said actuator plunger.

14. A switch mechanism comprising, in combination, a housing, switch means mounted in said housing, an actuator plunger on said switch means disposed along an axis, an end wall at one longitudinal end of said housing and having an interior and an exterior surface, a circular aperture through said end wall coaxial with said plunger axis, a removable and indexable head on said end wall of said housing, a cylindrical extension on said head closely fitting within said circular aperture, a shoulder wall defining a polygonal recess concentric with said aperture on one of said wall exterior and said head, boss wall means defining a polygonal boss on the other of said wall exterior surface and said head and concentric with said aperture and entering said polygonal recess to mate closely therewith, wall means including an annular shoulder defining an annular groove on said cylindrical extension and disposed inboard of the interior surface of said housing end wall to be within said housing, a generally flat leaf spring having a forked end with the bight of the fork having a dimension slightly larger than the diameter of said annular groove to be received in said annular groove, said forked end being bent at a small angle so that the two ends of the fork engage said interior surface of said housing end wall and the bight of the fork engages said annular shoulder of said annular groove to resiliently urge said head inwardly of said housing, whereby said head may be pulled longitudinally outwardly to stress said spring and to cause said boss to be removed from said recess to permit indexing of said head into any one of a number of plural positions equal to the number of sides of said polygonal recess, aperture means in said cylindrical extension coaxial therewith, and an actuator link in said head disposed for longitudinal sliding movement through said aperture means in said cylindrical extension to actuate said actuator plunger.

15. A switch mechanism comprising, in combination, an elongated housing with a longitudinal axis, an end wall at one longitudinal end of said housing, a circular aperture through said end wall parallel to the longitudinal axis of said housing, a shoulder wall defining a polygonal recess on the exterior surface of said end wall concentric with said aperture, a removable and indexable head on said end wall of said housing, a cylindrical extension on said head closely fitting within said circular aperture, boss wall means defining a polygonal boss on said head concentric with said cylindrical extension and entering said polygonal recess on said housing and wall to mate closely therewith, wall means defining an annular groove on said cylindrical extension and disposed inboard of the inner surface of said housing end wall to be within said housing, a generally flat leaf spring having a forked end with the bight of the fork generally semicircular and of a radius slightly larger than the radius of said annular groove to be received in said annular groove, said leaf spring being generally rectangular in outline to be received in close proximity to the rectangular inner surface of said housing end wall, said forked end being bent at a small angle so that the two ends of the fork engage said inner surface of said housing end wall and the bight of the fork engages the wall means defining said annular groove to resiliently urge said head inwardly of said housing, whereby said head may be pulled longitudinally outwardly to stress said spring and to cause said boss to be removed from said recess to permit indexing of said head into any one of four positions 90 degrees apart, switch means mounted in said housing, an actuator plunger on said switch means disposed along the axis of said circular aperture, aperture means in said cylindrical extension coaxial therewith and disposed parallel to said longitudinal axis, an actuator link in said head disposed for longitudinal sliding movement along the axis of said cylindrical extension and through said aperture means in said cylindrical extension to actuate said actuator plunger, and an actuator roller on an exterior end of said actuator link for external engagement.

said forked end being bent at a small angle so that the two ends of the fork engage said inner surface of said housing end wall and the bight of the fork engages the wall means defining said annular groove to resiliently urge said head inwardly of said housing, whereby said head may be pulled longitudinally outwardly to stress said spring and to cause said boss to be removed from said recess to permit indexing of said head into any one of a number of plural positions equal to the number of sides of said polygonal recess, switch means mounted in said housing, an actuator plunger on said switch means disposed along the axis of said circular aperture, aperture means in said cylindrical extension coaxial therewith and disposed parallel to said longitudinal axis, an actuator link in said head disposed for longitudinal sliding movement through said aperture means in said cylindrical extension to actuate said actuator plunger.

16. An industrial switch mechanism comprising, in combination, an elongated generally rectangular hollow housing with a longitudinal axis, an end wall at one longitudinal end of said housing, the inner surface of said end wall being rectangular, a circular aperture through said end wall parallel to the longitudinal axis of said housing, a shoulder wall defining a square recess on the exterior surface of said end wall concentric with said aperture, a removable and indexable head on said end wall of said housing, a cylindrical extension on said head closely fitting within said circular aperture, boss wall means defining a square boss on said head concentric with said cylindrical extension and entering said square recess on said housing and wall to mate closely therewith, wall means defining an annular groove on the exterior cylindrical surface near the outer end of said cylindrical extension and disposed inboard of the inner surface of said housing end wall to be within said housing, a generally flat leaf spring having a forked end with the bight of the fork generally semicircular and of a radius slightly larger than the radius of said annular groove to be received in said annular groove, said leaf spring being generally rectangular in outline to be received in close proximity to the rectangular inner surface of said housing end wall, said forked end being bent at a small angle so that the two ends of the fork engage said inner surface of said housing end wall and the bight of the fork engages the wall means defining said annular groove to resiliently urge said head inwardly of said housing, whereby said head may be pulled longitudinally outwardly to stress said spring and to cause said boss to be removed from said recess to permit indexing of said head into any one of four positions 90 degrees apart, switch means mounted in said housing, an actuator plunger on said switch means disposed along the axis of said circular aperture, aperture means in said cylindrical extension coaxial therewith and disposed parallel to said longitudinal axis, an actuator link in said head disposed for longitudinal sliding movement along the axis of said cylindrical extension and through said aperture means in said cylindrical extension to actuate said actuator plunger, and an actuator roller on an exterior end of said actuator link for external engagement.

17. An industrial switch mechanism comprising, in combination, an elongated generally rectangular hollow housing with a longitudinal axis,

an end wall at one longitudinal end of said housing, the inner surface of said end wall being rectangular, a circular aperture through said end wall parallel to the longitudinal axis of said housing, a square recess on the exterior surface of said end wall 5 concentric with said aperture, a removable and indexable head on said end wall of said housing, a cylindrical extension on said head entering and closely fitting within said circular aperture, a square boss on said head concentric with said cylindrical extension and entering said square recess on said housing and wall to mate closely therewith, wall means defining an annular groove on the exterior cylindrical surface near the outer end of said cylindrical extension and disposed inboard of the interior surface of said housing end wall to be within said housing, 15 a generally flat leaf spring having a forked end and an apertured end, said forked end having the bight of the fork generally semicircular and of a radius slightly larger than the radius of said annular groove to be received in said annular groove, said leaf spring being generally rectangular in outline 20 to be received in close proximity to the rectangular inner surface of said housing end wall, said apertured end of said leaf spring permitting grasp- 25

ing of the leaf spring to permit its removal from said annular groove and from said housing, said forked end being bent at approximately a 10 degree angle so that the two ends of the fork engage said inner surface of said housing end wall and the bight of the fork engages the wall means defining said annular groove to resiliently urge said head inwardly of said housing, whereby said head may be pulled longitudinally outwardly to stress said spring and to cause said boss to be removed from said recess to permit indexing of said head into any one of four positions 90 degrees apart, switch means mounted in said housing, an actuator plunger on said switch means disposed along the axis of said circular aperture, cam means in said head, aperture means in said cylindrical extension coaxial therewith and disposed parallel to said longitudinal axis, link means in said aperture means to act between said cam means and said actuator plunger to actuate same upon rotation of said cam means, and an actuating lever pivotally mounted in said head to rotate said cam.
